CLAIM

The ornamental design for a sample processor card for
use in chemical analysis apparatus, substantially as
shown and described.

DESCRIPTION

FIG. 1 is a top perspective view of a sample processor
card for use in chemical analysis apparatus, showing my
new design;

FIG. 2 is a top plan view thereof;

FIG. 3 is a rear elevational view thereof;

FIG. 4 is a side elevational view thereof;

FIG. 5 is a front elevational view thereof; and

FIG. 6 is a bottom plan view thereof.

FIG. 3

FIG. 2

FIG. 4

FIG. 1

FIG. 5

FIG. 6
